UNITED STATES PATENT OFFICE.

PAUL LUX, OF WATERBURY, CONNECTICUT, ASSIGNOR TO THE WATERBURY CLOCK CO., OF WATERBURY, CONNECTICUT, A CORPORATION.

ALARM-CLOCK.

No. 869,376.

Specification of Letters Patent.

Patented Oct. 29, 1907.

Application filed August 28, 1907. Serial No. 390,491.

To all whom it may concern:

Be it known that I, PAUL LUX, a citizen of the United States, residing at Waterbury, in the county of New Haven and State of Connecticut, have invented a new and useful Improvement in Alarm-Clocks; and I do hereby declare the following, when taken in connection with the accompanying drawings and the letters of reference marked thereon, to be a full, clear, and exact description of the same, and which said drawings constitute part of this specification, and represent, in—

Figure 1 a reverse plan view of a clock-movement provided with my improvement, only such parts of the trains being shown as is necessary to illustrate the relation of my improved mechanism thereto. Fig. 2 a view 15 in vertical section on the line *a--b* of Fig. 1 looking from rear to front. Fig. 3 a corresponding view on the line *c--d* of Fig. 1.

My invention relates to an improvement in that class of alarm clocks in which provision is made for readily 20 converting the clock from a long or continuous alarm clock to an intermittent or spasmodic alarm clock, the object being to produce a simple, compact, reliable and convenient mechanism constructed with particular reference to being embodied in very small circular clocks 25 of the kind commonly placed in nickelized sheet metal cases and known to the trade as "nickel" clocks.

With these ends in view my invention consists in a clock having certain details of construction and combinations of parts as will be hereinafter described and 30 pointed out in the claims.

In carrying out my invention as herein shown, I employ an alarm wheel 2 which turns from left to right with the shaft 3 of the third wheel 4 of the time-train which may be of any ordinary construction. The teeth of the 35 wheel 2 co-act with the beveled nose of an alarm lever 5 constantly pressed toward the said wheel by a spring 6 secured to the front face of the intermediate movement-plate 7. The lever 5 is mounted upon the projecting front end of an oscillating alarm-staff 8 journaled at its 40 front end in the plate 7 and at its rear end in the rear movement-plate 9 and carrying a wire alarm stop arm 10 co-acting with a radially arranged alarm stop pin 11 carried by a large collet 12 on the staff 13 of the escape- 45 ment wheel 14 of the alarm-train which may be of any ordinary construction. The staff 8 also carries a wire alarm cut-off arm 15 extending in the opposite direction from the stop arm 10 and arranged to be engaged by the inner end of a sliding manual cut-off comprising a stud 16 mounted in a slot 17 in the rear movement plate 9 50 and projecting rearward through a slot 18 in the flanged

disk-like back 19 of the clock-case which, barring the said back, is not shown. A cupped friction washer 20 mounted upon the stud 16 engages with the front face of the plate 9 and holds the cut-off in its active and retired positions at the ends of the slot 17. When the cut-off is 55 moved from right to left its inner end rides over the cut-off arm 15 and so rocks the staff 8 sufficiently to move the stop arm 10 sufficiently outward to clear it from the outer end of the stop pin 11 so that when the alarm-train is let off it will run continuously until the alarm 60 spring runs down, for the reason that when the stop arm 10 is disengaged from the stop pin 11 the wheel 14 is free to rotate from left to right under the restraint of the verge 21 of the verge arbor 22 which carries the bell hammer 23 which is arranged in position to strike the 65 bell. The time and alarm trains and alarm let-off mechanisms of such clocks being well known, it has been deemed unnecessary to either show them or describe them.

To set the clock to operate as an intermittent or spasmodic alarm, the sliding cut-off is moved by the fingers from right to left so as to clear the cut-off arm 15. This leaves the spring 6 free to press the lever 5 toward the wheel 2. Now as the wheel 2 turns from left to right, its teeth will co-act with the beveled nose of the lever 5 75 and push the same outward against the power of the spring 6 whereby the staff 8 will be sufficiently turned on its axis to lift the stop arm 10 away from engagement with the stop pin 11. When the alarm-train is released in the usual manner, the alarm will be sounded until 80 the rotation of the wheel 2 by the time-train permits the lever 5 to drop off the next succeeding tooth of the wheel. When this occurs the spring 6 will act to move the lever 5 inward and thus rock the staff 8 so as to bring the end of the stop-arm 10 into the path of the stop pin 85 11 which will engage with the end of the arm 10 and stop the alarm-train which will, however, be released again just as soon as the time-train has operated through the wheel 2 to again lift the lever 5 for the disengagement of the stop arm 10 from the stop pin 11. This 90 cycle of operation will be continued until the alarm spring runs down. On the other hand, if it is desired to use the clock as a long or continuous alarm clock, the cut-off arm 15 will be moved from left to right, whereby the cut-off arm 15 will be engaged and crowded inwardly with 95 the effect of rocking the staff 8 so as to lift the end of the arm 10 away from the end of the stop pin 11 and so as to lift the beveled end of the lever 5 away from co-action with the teeth of the wheel 2. The alarm mechanism will now operate to sound a continuous alarm as though 100

the wheel 2, lever 5 and other co-acting parts were eliminated from the clock.

I claim:—

In a convertible alarm mechanism, the combination 5 with an alarm wheel operated by the time-train, of a spring-actuated lever co-acting with the teeth of the said wheel, an oscillating shaft by which the said lever is carried, a stop arm upon the said shaft, an alarm escape-
ment wheel, a stop pin rotating with the said wheel and

co-acting with the end of the said stop-arm, a cut-off arm 10 also carried by the said oscillating shaft, and a manual cut-off co-acting with the said cut-off arm for temporarily retiring the said lever and stop arm.

In testimony whereof, I have signed this specification in the presence of two subscribing witnesses.

PAUL LUX.
